HEEL-ATTACHING MACHINE

Fred L. MacKenzie, Beverly, Mass., assignor to
 United Shoe Machinery Corporation, Paterson,
 N. J., a corporation of New Jersey

Application March 17, 1932, Serial No. 599,481

12 Claims. (Cl. 1—32)

This invention relates to heeling machines, being particularly concerned with the mechanism by which pressure is applied to hold in place upon the heel-seat of a jacked shoe a heel which 5 is to be attached by nails driven from inside the shoe.

In machines of the character above indicated, there is customarily first applied by the operator a preliminary or measuring pressure, by which 10 a retaining head or abutment is brought into firm contact with a heel positioned upon a jacked shoe. Then the power-operation of the machine is started, and the heel is subjected to a final clamping pressure, intended to hold the 15 heel and shoe against displacement from the jack-top under the influence of the nails being driven through said jack-top and through the heel-seat into the heel. It is found difficult to apply this final pressure with sufficient force and 20 at the proper time to prevent separation of the work from the jack. If this movement is allowed to occur, the heads of the nails will not be sufficiently sunk in the insole, the crease not made as tight as is desirable, and there is a 25 tendency for the heel to be tilted forward upon the heel-seat, which causes the nails to be misdirected, they emerging through the periphery of the heel at the rear or splitting it. It is an object of my invention to subject the heels in 30 this class of work to ample pressure to resist the displacing force of the nails, and to a controllable degree for heels and shoes of different character, and to obtain this pressure in the correct 35 relation to the time of actuation of the nail-drivers. I achieve this end by combining with a jack, its co-operating work-clamping pressure-head and a driving shaft of the machine, a cam rotatable by the driving shaft and having at its periphery portions of different curvature, together 40 with a link or connecting member contacting with opposite sides of the cam, as through a spaced pair or pairs of opposite plates, and joined to the head. A cam thus acting upon the head may be caused to exert a direct force without 45 interposed elements, to create pressure upon the work and to remove such pressure without the employment of springs or the like. The cam may be of such contour, regardless of the manner in which its effect is transmitted, as to give 50 the chosen timing of the pressure with reference to the nail-insertion. I prefer to provide a cam with opposite concentric portions of different diameters and inclined intermediate portions. The difference in diameter of the concentric portions will give the desired clamping travel of the

head, and the intermediate inclination, which applies and removes the pressure, may be of relatively small circumferential extent, so the pressure-change occurs quickly as compared with the periods of rest of the head. During these periods, the nail-drivers make their advancing and retreating strokes, and a clutch device, which permits the separate application of preliminary and final pressure, may be locked and unlocked. Since heels and heel-seats having different characteristics call for the application of varying pressures, I may provide for forming the cam-surface of my invention upon an eccentric, this being surrounded by a strap or a portion of a link which is joined to the pressure-head. By 60 altering the throw of the eccentric, this is added to or subtracted from the effect of the cam, and the pressure imposed by the head is correspondingly changed.

One of the several embodiments of which my 75 invention is capable appears in the accompanying drawing. Here,

Fig. 1 shows in broken side elevation a portion of a heel-attaching machine to which my improved pressure mechanism is applied; and

Fig. 2 is a front elevation of said mechanism.

The general heeler-organization herein illustrated is similar to that of Letters Patent of the United States No. 1,545,575, Standish, July 14, 1925. Upon a frame 10 is carried a shoe-support 80 or jack 12, in which is a plunger 14 carrying nail-drivers 15 and reciprocated through a connecting-rod 16 from a crank-pin 18 upon the forward extremity of a power-shaft 20 journaled horizontally near the bottom of the frame. A shoe S 90 to be heeled may be placed heel-seat up upon the jack. Guided in vertical ways in the frame is a pressure-head 22 provided with contact members 24 and 26 for engagement with the tread- and rear surfaces, respectively, of a heel H positioned upon the heel-seat of the jacked shoe S. This pressure device may have means, as a spring, for holding it normally raised from the work, and treadle connections by which the members are lowered into preliminary contact with the heel. 95 But, as this invention deals wholly with the application of the final pressure under the power of the machine to clamp the heel so that it will resist the upward displacing force of the attaching nails as they are driven through the heel-seat into the heel, this elevating and measuring means is not herein illustrated.

For the creation of the final pressure by the head 22, it has depending from it a set of clutch-plates 28, spaced from each other; and inter- 105

leaved with these plates 28 is a second set of plates 30 joined to an eccentric-rod or connecting member 32 having its strap 34 surrounding the shaft 20. This strap is shown as made up of a laterally extended portion 36 at the lower end of the rod or link 32, opposite side-portions 38, 38 and a bottom-portion 40, these being secured by bolts 42, 42 in a form generally that of a square. To the inner faces of the strap-portions 38, 38 are attached contact-plates 44, 44, and upper and lower contact-plates 46, 47 are secured to the strap-portions 36 and 40, respectively. The active contact-surfaces 48 of these plates lie approximately along the sides of a square, those opposite each other being substantially parallel. Fast upon the shaft 20 within the strap 34 is an eccentric cam 50. To cause this device 50 to actuate the pressure-head 22 at the desired times, to effect the clamping and release of the heel H, its link 32 may be clutched to the head by producing frictional engagement between the plates 28 and 30. For this purpose, there is mounted in ways upon a downwardly extending portion of the head 22, opposite the interleaved portions of the plates 28 and 30, a slide 52, alined with which, at the outer ends of the ways, is a yieldable abutment 54. The elements 52 and 54 are connected by a toggle-lever 56, and the pivotal connection between these links is, in turn, joined by a link 58 to the upper extremity of a lever 60 fulcrumed upon an extension from the upper portion of the link 32. The lower end of the lever has rotatable upon it a roll 62 held yieldably forward by a spring 64 movable upon the frame in contact with a cam 66 fixed upon the shaft 20. The roll-engaging surface of the cam is of such contour as to cause the toggle 56 to be straightened and broken to force the plates 28 and 30 together or to separate them in the correct time-relation to the cam 50 and crank-pin 18. To allow the application of pressure to the work by the head 22 during the driving of the nails, or to unclutch the plates to allow the head to be raised for the application of the work or its removal from the jack, the distance between the opposite sides of the cam 50, considered along any diameter, is the same, so it will turn smoothly in contact with the plate-surfaces 48 to produce vertical movement of the link 32. It may be noted here that, since the only function of the side-plates 44, 44 is to prevent undue lateral displacement of the strap 32, there is preferably a slight clearance between the periphery of the cam and the surfaces 48 of the side-plates over that between said cam and the corresponding surfaces of the plates 46 and 47 through which the head 22 is actuated. In Fig. 2 of the drawings, the cam is shown in its normal position, or that which it occupies at the beginning of an operating cycle.

The peripheral surface of the cam is made up of four sections. From *a* to *b* is a circumferential portion *v* formed about the center *o*. From *c* to *d* is an opposite circumferential portion *w* having the same center *o* but being of greater diameter. The points *a* and *c* and *b* and *d* are respectively joined by surfaces *x* and *y* symmetrically located at opposite sides of the cam and being of relatively small peripheral extent, so the shift of the plates 46 and 47 between the surfaces *v* and *w* is quickly accomplished, to give the full throw of the link 32 in either direction. When the center of the cam 50 and the axis of the shaft 20 coincide, the movement imparted to the link 32 is equal to the difference between the radii of the portions *v* and *w*. This is sufficient to so lower

the head 22 that the minimum clamping pressure will be applied to hold the heel H upon the shoe S, this being all that is required for certain classes of work. When the character of the work changes and it is desired to increase the travel of the head, the cam 50 is made eccentric by shifting it, so its center no longer lies at the axis of the shaft 20. This may be accomplished by mounting the cam in the following manner: Its opening through which the shaft passes is bored at an angle to the axis and to the periphery of the cam, and this opening receives a correspondingly inclined sleeve 70 secured to the shaft. The sleeve is longer than the transverse dimension of the cam, so the latter may be varied in position on the sleeve between flanges 72, 72 fixed to the shaft at the opposite ends of said sleeve. Rotatable in the flanges 72 and threaded into the cam is a screw 74 having the same inclination as the contact-faces of the cam and sleeve. By rotating the screw through a slotted head 76, the cam may be shifted longitudinally of the sleeve to carry its center a greater or less distance from the axis of the shaft. The eccentricity thus produced will be added to the rise *a*, *c* and drop *d*, *b* of the cam to increase the travel of the pressure-head 22.

In the operation of a heel-attaching machine including this mechanism, the operating cycle ends with a point *z* upon the cam-surface *v* of minimum diameter in contact with the surface 48 of the lower strap-portion 47. This point *z* is removed by a short angular distance from the point *a* of the cam, which is rotatable in the direction indicated by the arrow in Fig. 2. Nails N having been placed in the driver-passages of the jack, the shoe S positioned upon said jack and the heel H applied to its heel-seat, the head 22 is preliminarily lowered to bring the members 24 and 26 into contact with the heel, and the power-operation is started for a single cycle. As the shaft 20 rotates, the driver-plunger 14 rises from the bottom of its stroke under the influence of the crank-pin 18. The points of the nails are initially preferably somewhat below the jack-top, and, before they reach the insole of the shoe, the cam 66 acts through the connections to the slide 52 to clutch the plates 28 and 30 together, so the link 32 and head 22 may travel downwardly as a unit. This locking of the head to the link takes place when the cam is rotating with the peripheral surface from *z* to *a* in engagement with the plate of the lower strap-portion 47, and the succeeding rotation from *a* to *c* causes the application to the work of the full clamping pressure during a short angular movement of the cam. At about the time this is completed, the points of the nails arrive at the insole of the shoe, and as the cam-surface *w* of maximum diameter moves over the plate 47 and the head rests in its clamping relation, the drivers force the nails through the heel-seat into the heel and then begin their downward travel. While this is in progress, the surface *y* of the cam, reaching the lower plate 47, permits the surface *x*, by engagement with the upper plate 46, to restore the head 22 to its normal elevated position. The heeled shoe will now be removed from the jack. During the final rotation of the cam 50, with the head 22 held raised, the cam 66 is unlocking the clutch-plates 28 and 30, and the driver-plunger is returning to its lowest point. When the point *z* has returned to the initial point, the machine is stopped and is ready for the succeeding operation. It will be seen that I have provided simple means by which the pressure-head of a heeling

machine may be positively and quickly moved into and out of work-clamping relation at such times that its full resistance is offered to driving force applied to the heel-attaching nails. Moreover, the extent of this movement may be varied to suit particular operating conditions without disturbing the established time-relation.

Having described my invention, what I claim as new and desire to secure by Letters Patent of the United States is:

1. In a heel-attaching machine, a jack, a pressure-head movable to clamp the work upon the jack, a driving shaft, a cam rotatable by the shaft and having at its periphery portions of different curvature, and a connecting member contacting with opposite sides of the differently curved periphery of the cam and being joined to the head.

2. In a heel-attaching machine, a jack, a pressure-head movable to clamp the work upon the jack, a driving shaft, a cam rotatable by the shaft and having upon its peripheral surface opposite concentric portions of different diameters and inclined portions between the concentric portions, and a connecting member movable by such peripheral surface and joined to the head.

3. In a heel-attaching machine, a jack, a pressure-head movable to clamp the work upon the jack, a driving shaft, a cam rotatable by the shaft, and a connecting member contacting with opposite sides of the cam and being joined to the head, the cam having upon its surface engaged by the connecting member opposite concentric portions of different diameters and inclined portions between the concentric portions.

4. In a heel-attaching machine, a jack, a pressure-head movable to clamp the work upon the jack, a driving shaft, a cam rotatable by the shaft and having upon its peripheral surface opposite concentric portions of different diameters and inclined portions between the concentric portions, the difference in diameter of the concentric portions corresponding to the clamping travel of the head, and a connecting member movable by such peripheral surface and joined to the head.

5. In a heel-attaching machine, a jack, a pressure-head movable to clamp the work upon the jack, a driving shaft, a cam rotatable by the shaft and having upon its peripheral surface opposite concentric portions of different diameters and each of considerable circumferential extent and inclined portions of relatively small circumferential extent between the concentric portions, and a connecting member movable by such peripheral surface and joined to the head.

6. In a heel-attaching machine, a jack, a pressure-head movable to clamp the work upon the jack, a driving shaft, a cam rotatable by the shaft

and having upon its peripheral surface opposite concentric portions of different diameters and inclined portions between the concentric portions, a clutch interposed between the connecting member and head, and means for operating the clutch while the concentric portions of the cam are acting upon the connecting member.

7. In a heel-attaching machine, a jack, a pressure-head movable to clamp the work upon the jack, a driving shaft, a cam rotatable by the shaft and having differently curved peripheral portions, and a link connected to the head and having a portion surrounding the cam, said portion contacting with the periphery thereof at certain points and being separated therefrom at other points.

8. In a heel-attaching machine, a jack, a pressure-head movable to clamp the work upon the jack, a driving shaft, a cam rotatable by the shaft and having differently curved peripheral portions, a link connected to the head and having a portion surrounding the cam, and opposite plates carried by the surrounding portion for contact with the cam and being substantially parallel to each other.

9. In a heel-attaching machine, a jack, a pressure-head movable to clamp the work upon the jack, a driving shaft, a cam rotatable by the shaft, a link connected to the head and having a portion surrounding the cam, and pairs of plates spaced from one another about the surrounding portion for the contact with the cam and corresponding substantially to the sides of a square.

10. In a heel-attaching machine, a jack, a pressure-head movable to clamp the work upon the jack, a driving shaft, an eccentric rotatable by the shaft and provided with cam-projections, and a link having a portion surrounding the eccentric and being joined to the head.

11. In a heel-attaching machine, a jack, a pressure-head movable to clamp the work upon the jack, a driving shaft, an eccentric rotatable by the shaft and provided with cam-projections, means arranged to vary the throw of the eccentric, and a link having a portion surrounding the eccentric and being joined to the head.

12. In a heel-attaching machine, a jack, a pressure-head movable to clamp the work upon the jack, a driving shaft, a member having an inclined peripheral surface and being rotatable by the shaft, an eccentric movable upon such inclined surface longitudinally of the shaft and provided with cam-projections, means carried by the shaft and arranged to move the eccentric, and a link having a portion surrounding the eccentric and being joined to the head.
